(57) **CLAIM**

The ornamental design for a bucket opener, as shown.

DESCRIPTION

FIG. 1 is a perspective view showing my new design;
 FIG. 2 is a left side view thereof;
 FIG. 3 is a top plan view thereof;
 FIG. 4 is a front view thereof;
 FIG. 5 is a right side view thereof;
 FIG. 6 is a bottom plan side view thereof;
 FIG. 7 is a rear view thereof; and,
 FIG. 8 is a perspective view showing the bucket opener removing the lid of a bucket.
 The broken line showing of the bucket illustrates the unclaimed environment of the bucket opener and forms no part of the claimed design.
